FRICTION WINDING CORE

John Ryer Dunham, Highland Park, N. J., assignor to John Waldron Corporation, New Brunswick, N. J., a corporation of New Jersey

Application September 18, 1934, Serial No. 744,584

3 Claims. (Cl. 242—75)

This invention relates to friction winding cores.

In many industries where paper, cloth or other material are wound on paper, wood or metal cores, it is generally customary to wind a plurality of rolls or bundles on one shaft or spindle. Upon the completion of the winding operation the material and its core are removed. This is sometimes cumbersome and difficult to accomplish. In addition, the friction or tension is usually on one end of the winding shaft. Also the difficulties increase to a certain extent in connection with the number of strips of material being wound.

One of the objects of this invention is to provide friction winding cores having individual tension in connection with each winding core.

Another object of the invention is to provide a friction winding core of simple construction permitting easy spacing of the cores on the shaft and ready removal of the cores bearing the material.

A further object of the invention is to provide quick threading or attachment of material to the core.

25 Referring to the drawing:

Figure 1 is a view in front elevation partly in section along the line 1, 1, of Figure 2.

Figure 2 is a view in cross section of Figure 1 along the line 2, 2, looking in the direction of 30 the arrows.

In carrying out my invention, I provide a steel sleeve 1 which is journaled on the winding shaft or spindle of the winding machine. Encircling steel sleeve 1 is a collar 2. Also encircling steel 35 sleeve 1 is the main body 3 of the winding core. Between body 3 and collar 2 is a circular felt friction ring 4. On the opposite end is a threaded portion 5 upon which is screwed a nut 6. Spanner holes 7 are formed in the face of nut 40 6. Between nut 6 and main body portion 3 is a steel washer 8 and between steel washer 8 and main body portion 3 is another felt friction ring 4'. An encircling coil adjustment spring 9 is interposed between washer and the sloping rear 45 face 10 of nut 6. Body portion 3 has two chambers 11 formed exteriorly to hold serrated edge friction wheels 12 which are supported by shafts 13 journaled in the main body portion 3. Chamber 11 is slightly larger in diameter than the serrated wheels 12 to permit a limited side sliding motion of the serrated wheel 12. Threaded exteriorly to body portion 3 are flanges 14, 14'. Either flange may be independently removed. Between flanges 14, 14', and encircling body portion 3 is the winding core 15. The internal di-

ameter of the winding core 15 is sufficient when one of the flanges is removed to permit ready insertion over the serrated wheels 12, the wheels rotating to permit insertion. After the core 15 is placed on body portion 3 and the flange 14' is again put in position, the serrated wheels 12 through their serrated surface grip the core to provide rotation for the winding of the material. The width of chamber 11 permits the serrated wheel 12 to slide endwise on shaft 13 and thereby increases the driving power of the wheels because as they slide along shaft 13 such motion increases the diameter thereby increasing the grip of the serrated surfaces against the inside of the paper core 15. It being understood that the paper core 15 is thereby caused also to be frictionally pressed against the external surface of body portion 3, particularly opposite to wheels 12.

Where narrow strips of material are wound it is difficult to secure the strips to the paper core. I therefore propose to provide a gummed flap 16 of considerable length which is attached at one end to the material and at the other end is wound on the external surface of paper core 15 to thread the material between flanges 14, 14', in order to start the wrapping of the bundle. The gummed flap 16 need only be allowed to contact with the rotating core without tension and the surface of the core will then pick it up and after one or two rotations the gummed flap 20 16 becomes tightly secured enabling the completion of the winding of the material. Body portion 3 is frictionally driven by steel sleeve 1. This is accomplished by drawing up on nut 6 which compresses coil adjustment spring 9 against the 25 steel washer 8 which in turn bears against felt ring 4', while at the same time collar 2 bears against friction ring 4 to clamp the body portion 30 between nut 6 and collar 2. The tension and therefore the friction, can be adjusted by such 35 construction and nut 6 is not easily accidentally displaced.

It will thus be seen that I have invented a frictional winding core device which permits of easy insertion of the core on the winding shaft 45 and the same easy withdrawal upon the completion of the winding of the material and at the same time provides a friction drive for the winding core to permit the winding up of the material which friction drive is of a positive nature 50 so that no slippage will occur and the core may be driven in either direction of rotation.

I have also provided means for threading the material to be wound on the winding core.

Various modifications may be made and still 55

fall within the scope of my invention. For instance, the side flanges 14, 14', may have one or both omitted particularly where wide webs are being wound.

5 What I claim is:

1. In a device for winding paper, a sleeve, a body portion encircling said sleeve, means for frictionally securing said body portion to said sleeve, means rotatable to permit the sliding onto 10 said body portion of a core and to drive said core with said body portion by frictionally gripping said core.

2. In a device for winding materials into rolls, a sleeve, a body portion surrounding said sleeve and frictionally driven by said sleeve, a chamber 15 in said body portion, a serrated roll in said chamber and projecting beyond the surface of said body portion, a core insertable around said body

portion roll, means for increasing the driving power on said core, and flanges carried by said body portion extending beyond said core to prevent telescoping of the material being wound.

3. In a device for winding materials into rolls, 5 a sleeve, a body portion surrounding said sleeve and frictionally driven by said sleeve, a chamber in said body portion, a serrated roll in said chamber and projecting beyond the surface of said body portion, a core insertable around said body 10 portion roll, means for increasing the driving power on said core, and flanges carried by said body portion extending beyond said core to prevent telescoping of the material being wound, and means for securing and threading the material to 15 the core.

JOHN RYER DUNHAM.
